[57] CLAIM

The ornamental design for a comforter having a stitch pattern, as shown and described.

DESCRIPTION

FIG. 1 is an isometric view of a first embodiment of the comforter having a stitch pattern showing my new design; FIG. 2 is a top plan view thereof, the bottom plan view being identical thereto;

FIG. 3 is a head end elevational view thereof;

FIG. 4 is a foot end elevational view thereof;

FIG. 5 is a side elevational view thereof, both side elevational views being identical;

FIG. 6 is an isometric view of a second embodiment of the comforter showing my new design;

FIG. 7 is a top plan view thereof, the bottom plan view thereof being identical thereto;

FIG. 8 is an end elevational view thereof, both end elevational views being identical; and,

FIG. 9 is a side elevational view thereof, both side elevational views being identical.
